ELASTIC FABRIC

Filed April 16, 1936

FIG. 1.

FIG. 2.

INVENTOR:
Harry H. Busch
BY *Alfred E. Pehinger*,
ATTORNEY.

UNITED STATES PATENT OFFICE

100,153

DESIGN FOR ELASTIC FABRIC

Harry H. Busch, Wyomissing, Pa., assignor to
The Narrow Fabric Company, West Reading,
Pa., a corporation of Pennsylvania

Application April 16, 1936, Serial No. 62,166

Term of patent 7 years

To all whom it may concern:

Be it known that I, Harry H. Busch, a citizen of the United States of America, residing at Wyomissing, in the county of Berks and State of Pennsylvania, have invented a new, original, and ornamental Design for Elastic Fabric, of which the following is a specification, reference being had to the accompanying drawing, forming part thereof.

Figure 1 discloses a portion of an unstretched elastic fabric embodying my ornamental design.

Fig. 2 discloses a portion of the elastic fabric depicted in Fig. 1, as it appears when subjected

to tension substantially equivalent to that incident to normal use.

The figures disclose the elastic fabric enlarged to approximately one and one-half times normal size, so that they will be approximately full size upon the reduction of the same to the ultimate size as appearing in the patent copy.

I claim:

The ornamental design for elastic fabric as shown and described.

In testimony whereof I affix my signature.

HARRY H. BUSCH.
